UNITED STATES PATENT OFFICE

GEORGE E. LAND, OF PITTSBURGH, PENNSYLVANIA, ASSIGNOR, BY MESNE ASSIGNMENTS, TO MARY HAINES MARKS, OF SEWICKLEY, PENNSYLVANIA

REENFORCING BASE FOR PLASTIC MATERIAL

Application filed May 8, 1930. Serial No. 450,680.

My invention relates to wall construction, and more particularly to a reenforcing base for plastic material. I provide a reenforced base for plastic material consisting of a sheet of fibrous material such as paper, having spaced grooves therein for assisting in holding the plaster in place that have stiffening or reenforcing members associated therewith, said stiffening or reenforcing members being intimately secured to the side of the sheet away from the plaster by the same operation by which the grooves are formed.

The present invention is an improvement in the base for plastic material of my co-pending application Serial No. 359,481, filed May 1, 1929.

Modifications of my invention are shown in the accompanying drawing, in which

Figure 1 is a view in side elevation of a portion of a wall partly broken away;

Figure 2 is a cross-sectional view of the portion of the wall illustrated in Figure 1; and

Figures 3, 4, 5, and 6 are cross-sectional views of bases constructed in accordance with my invention, showing various shapes of grooves.

A sheet of paper less than three-sixteenths of an inch in thickness will not of itself support a layer of plaster because of its lack in inherent strength. Heretofore metal strips have been used to reenforce and strengthen a sheet of paper so that it can be used as a plaster base. In all of the methods heretofore used to associate the metal reenforcing member with the paper, the strips have been separate parts of the whole and the means used to hold the strips in place have been costly and slow.

I provide a reenforced plaster base in which the reenforcing strips are of the same shape as the grooves or corrugations and in which the reenforcing strips are attached to the paper and shaped to the form of the grooves by the same press operation.

Referring to the drawing, a sheet of paper 2 is provided with corrugations 3 to the outer side of which are attached metallic reenforcing channels 4 of the same shape as the corrugations 3. The reenforcing members 4

are intimately secured to the sheet 2 by means of prick punches 5.

In the manufacture of the plaster base 1, the paper as it comes from the mill is associated with flat strips of metal that are placed in the position at which the grooves are to be formed. The grooves or corrugations are then made in the paper and metallic strips by one operation. By the same operation, the metallic strips are punched to thereby secure the strips to the paper.

The metallic reenforcing members may, of course, be cemented or glued to the paper to form an intimate union between the two.

The grooves may be of various shapes; for example, Figure 3 shows grooves of V-shape, Figure 4 shows grooves of U-shape, Figure 5 shows grooves of semi-circular channel shape, and Figure 6 shows grooves of exaggerated U-shape.

Where a groove of an exaggerated U-shape is used, as shown in Figure 6, the metallic reenforcing members 6 are held in place by the shape of the groove.

The ribs or grooves are preferably formed in the direction of the natural grain of the paper, the grooves being spaced parallel about two inches apart.

Referring to Figures 1 and 2, the reenforced plaster base 1 is secured to a spaced vertical joist 7 by means of nails 8 that are journaled through the bottom of the grooves 3 and the reenforcing members 4 into the joist 7.

Vertical members 9 may be used either to add transverse rigidity or to reenforce a layer of plaster 10 that is placed on the base 1. Commercial reenforcing materials, such as metal lath or wire netting, may be attached to the backing by means of staples. It will be understood, however, that the attaching may be accomplished by lips integral with but extending from the stiffening members through the fibrous material and engaging the vertical members 9 or the commercial reenforcing materials.

The corrugations in the plaster base 1 serve to space the inner side of the base away from the joist 7 a distance that is approximately 100

equal to the thickness of a conventional wood lath.

In my plaster backing, I provide maximum transverse rigidity as well as maximum longitudinal rigidity in an inexpensive operation.

I further provide for corrugating the paper and fixing the stiffening members in one operation. In addition to the above, a plaster backing is provided which presents an unbroken surface for the reception of a layer of plaster. This improves the bond between the base and the plaster.

While I have illustrated and described preferred forms of my invention, it will be understood that it is not thus limited, but may be otherwise practiced and embodied within the scope of the following claims:

I claim:

1. A backing for plastic material comprising a sheet of fibrous material having spaced parallel corrugations therein and stiffening members for said grooves having integral means extending into the body of said sheet for securing said members to said sheet.
2. A backing for plastic material comprising a sheet of paper having parallel spaced grooves therein extending in the direction of the natural grain of the paper and stiffening members of the same shape as the grooves and means uniting said stiffening members to the paper, said means being disposed exclusively on the side of the paper away from the plaster side.
3. A backing for plastic material comprising a sheet of fibrous material having spaced parallel grooves therein and stiffening members intimately associated with said grooves, the stiffening members having lips which penetrate the fibrous material and engage plaster-reenforcing and backing-stiffening means.
4. A backing for plastic material comprising a sheet of fibrous material having spaced parallel grooves therein and stiffening members intimately associated with said grooves, the stiffening members having lips which penetrate the fibrous material and engage plaster-reenforcing and backing-stiffening means, the grooves being in the direction of the grain of the fibrous material.

In testimony whereof I have hereunto set my hand.

GEORGE E. LAND.
